CLAIM

The ornamental design for a filtering face-piece respirator support structure, as shown and described.

DESCRIPTION

FIG. 1 is a perspective view, showing the new design for a filtering face-piece respirator support structure;

FIG. 2 is a front view thereof;

FIG. 3 is a rear view thereof;

FIG. 4 is a left side view, the right side view being a mirror image thereof;

FIG. 5 is a top view thereof; and,

FIG. 6 is a bottom view thereof.

The broken line showing forms no part of the claimed design.
